(74) *Attorney, Agent, or Firm* — Carol N. Green, Esq.

CLAIM

The ornamental design for a computer screen with icon, as shown and described.

DESCRIPTION

FIG. 1 is a front view of a computer screen with icon.

FIG. 2 is a perspective view of the computer screen with icon.

FIG. 3 is a second perspective view of the computer screen with icon.

FIG. 4 is another embodiment of the computer screen with icon; and,

FIG. 5 is another embodiment of the computer screen with icon.

The outer broken lines in FIGS. 1-5 are representative of a portion of the computer screen and form no part of the claimed design.

1 Claim, 3 Drawing Sheets
